Geo. P. Kimmel.
ATTORNEY.

UNITED STATES PATENT OFFICE

MAUD HIX, OF CHILDRESS, TEXAS

GAME APPARATUS

Application filed October 3, 1930. Serial No. 486,323.

This invention relates to a game apparatus designed primarily for playing the game of tricket, but it is to be understood that a game apparatus in accordance with this invention may be employed for the playing of any games for which it is found applicable, and the invention has for its object to provide, in a manner as hereinafter set forth an apparatus of the class referred to for affording thrills, pleasure, amusement and excitement, when employing the same for playing any game for which the apparatus is applicable and further requiring on the part of the player dexterity, alertness and skill for successful playing of the game with which the apparatus is employed.

Further objects of the invention are to provide, in a manner as hereinafter set forth, a game apparatus which is simple in its construction and arrangement, strong, durable, compact, amusing when used, formed of few parts, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of the walled playing field forming element.

Figure 2 is a section on line 2-2 Figure 1.

Figure 3 is a section on line 3-3 Figure 1.

Figure 3A is an elevation of the set of player pieces.

Figure 4 is an elevation of the striker element.

Figure 5 is a vertical sectional view of the interrupter.

The walled playing field forming element comprises a triangular shaped body portion of skeleton form and referred to generally at 1, and which includes a pair of side walls 2,

3 and rear wall 4. The side walls 2, 3 extend towards each other at an inclination from the ends of the rear wall 4 and said side walls 2, 3 are connected together at their forward ends. The side walls 2, 3 and rear wall 4 provide a playing field 5 when said body portion is positioned upon the ground or on a support.

Projecting forwardly from the inner face of the rear wall 4 is a pair of oppositely extending, inclined, vertically disposed wall forming members 6, 7 which incline toward each other and have their forward ends arranged in spaced relation. Secured to the forward ends of the members 6, 7 is a wicket 8 of less height than either member 6, to provide a reduced entrance opening for the goal. The members 6, 7 in connection with the rear wall 4 and wicket 8 form a goal 9 which is arranged at the rear of and centrally with respect to the walled playing field forming element.

Connected to the wall forming members 6, 7 and extending to the side walls 2, 3 of the body portion 1 is a pair of anchoring members 10, 11 arranged rearwardly with respect to the forward ends of the wall forming member 6, 7. Connected to the anchoring members 10 and extending to and secured against the inner face of the rear wall 4 are flexible rebound members 12, 13 for the player pieces and which incline downwardly and extend forwardly from the rear wall 4 to the anchoring members 10, 11. The walls 2, 3 and 4 of the body portion 1 constitute a confining means for the player pieces to be presently referred to. The flexible members 12, 13 provide means for rebounding a player piece therefrom and which will be hereinafter referred to.

The apparatus includes a set of player pieces, preferably six in number, but this number can be increased or diminished and each of the player pieces is of spherical contour. The player pieces are indicated at 14, 15, 16, 17, 18 and 19. The player piece 14 is of materially greater diameter than any of the other player pieces. The player pieces 15 to 19 are of the same diameter. The player pieces are constructed of metal. The player

pieces 15 to 19 are formed of non-magnetic material. The player piece 14 if desired can be formed of magnetic material. The player piece 14 is termed an interrupter member and 5 the player pieces 15 to 19 are termed scoring members. The player piece 14 is of a diameter to prevent it from passing through the wicket 8. The player pieces 15 to 19 are of a diameter to pass through the wicket 8 and 10 into the goal 9. The player piece 14 is weighted and for such purpose one-half of the player piece 14 may be hollow and the other half solid.

The striker element comprises a staff 20 which can be differently colored and is provided at one end with a head 21 formed with a spherical extension 22 of any suitable size and which if desired can possess a characteristic to attract the player piece 14.

20 When the apparatus is used, it is the object of the player to project by the striker member the scoring members into the goal, but before striking a scoring member, it is essential to strike the interrupter member, or 25 in other words, a scoring member cannot be projected by the striker element until the interrupter member has been projected. The interrupter member is directed against a rebound member and the latter acts to return 30 the interrupter member into the playing field to interfere with the passage of that scoring member which has been struck.

The game may be played with each player having a limited number of strokes or it can 35 be played whereby the winner will be the one that projects the scoring members into the goal 9 with the smaller number of strokes but it is essential that a scoring member can only be struck by the striker element immediately 40 after the player has struck the interrupter member. The rebound members 12 and 13 also act to return the scoring members to the playing field when such members do not enter the goal 9.

45 Owing to the manner of using the apparatus it necessitates the player to be dexterous, alert, and skillful to quickly position or drive the scoring members into the goal 9, due to the fact that it is required of the player to strike 50 the interrupter member before the scoring member is struck to attempt to goal the latter. It is thought the many advantages of a game apparatus, in accordance with this invention can be readily understood, and although the 55 preferred embodiment of the invention is as illustrated and described, yet it is to be understood that changes in the details of construction can be had which fall within the scope of the invention as claimed.

60 What I claim is:

1. In a game apparatus of that type including driven balls, the combination of a skeleton element of triangular form standing on a lengthwise edge thereof and adapted to be 65 positioned upon a supporting surface to pro-

vide a walled playing field of triangular contour upon which the balls are driven, means within and positioned centrally of and projecting forwardly from one wall of said element and in connection with the latter providing a closed rear end goal, and a pair of upstanding flexible ball rebounding members positioned within said element and projecting forwardly from and having their upper ends secured to said wall, each of said members abutting one side of said means and another wall of said element, inclining downwardly and forwardly from its upper to its lower end and extending to and having its lower end anchored in said supporting surface. 70 75 80

2. In a game apparatus of that type including driven balls, the combination of a skeleton element of triangular form standing on a lengthwise edge thereof and adapted to be 85 positioned upon a supporting surface to provide a walled playing field of triangular contour upon which the balls are driven, means within and positioned centrally of and projecting forwardly from one wall of said element and in connection with the latter providing a closed rear end goal, and a pair of upstanding flexible ball rebounding members positioned within said element and projecting forwardly from and having their upper 95 ends secured to said wall, each of said members abutting one side of said means and another wall of said element, inclining downwardly and forwardly from its upper to its lower end and extending to and having its lower end anchored in said supporting surface, said members being of less height than that of said means and walls. 100

3. In a game apparatus of that type including driven balls, the combination of a skeleton element of triangular form standing on a lengthwise edge thereof and adapted to be 105 positioned upon a supporting surface to provide a walled playing field of triangular contour upon which the balls are driven, means within and positioned centrally of and projecting forwardly from one wall of said element and in connection with the latter providing a closed rear end goal, and a pair of upstanding flexible ball rebounding members positioned within said element and projecting forwardly from and having their upper 110 ends secured to said wall, each of said members abutting one side of said means and another wall of said element, inclining downwardly and forwardly from its upper to its lower end and extending to and having its lower end anchored in said supporting surface, and said goal having closed sides and an entrance opening at its front of less 115 height than that of the sides thereof. 120 125

4. In a game apparatus, a plural wall forming element of skeleton form for mounting on a supporting surface to provide a walled playing field, means within and posi- 130

tioned centrally of and projecting forwardly from one wall of said element and providing in connection with the latter a goal closed at its sides and rear and having a reduced entrance opening at its front, a pair of forwardly extending and downwardly inclined flexible rebound members within said element and having their upper ends secured to said wall and their lower ends anchored to said supporting surface and each abutting one side of said means and another wall of said element, a set of spherical scoring members for traversing said field to be goaled, and a spherical interrupter member of greater diameter than any one of the scoring members, of a diameter greater than the width and height of said entrance opening to prevent its passage through the latter and for traversing said field to impact against and rebound from said flexible members and for interrupting the travel of the scoring members.

In testimony whereof, I affix my signature hereto.

MAUD HIX.
